UNITED STATES PATENT OFFICE

ROGERS T. STAFFORD, OF EAST PROVIDENCE, RHODE ISLAND, ASSIGNOR TO B. A. BALLOU & CO., INC., OF PROVIDENCE, RHODE ISLAND, A CORPORATION OF RHODE ISLAND

PIN STEM

Application filed March 1, 1930. Serial No. 432,436.

This invention relates to certain new and useful improvements in pin stems for beauty pins, brooches and the like; and the object of this invention is to provide a pin stem of this character which is arranged to be pivotally mounted in the joint of a brooch, or the like, with means to which a connector member may be attached.

A further object of the invention is to provide a pin stem having a shank portion and a head portion, the head portion being pierced to receive a pivot and also being provided with a portion or ear also having a hole to receive a connector member.

With these and other objects in view, the invention consists of certain novel features of construction, as will be more fully described, and particularly pointed out in the appended claims.

In the accompanying drawings:

Fig. 1 is a view illustrating my improved pin stem as mounted on a base member of a beauty pin or the like, and being pivoted at one end in the joint member and engaging a catch member at its opposite end.

Fig. 2 is a perspective view of a pin stem blank cut from sheet stock.

Fig. 3 shows the shank as being rounded and pointed at one end and having a pierced, flat head at the other end and also having a pierced ear arranged on the periphery of the head.

Fig. 4 shows the pierced ear located beneath the axis of the shank portion.

Fig. 5 shows the pin stem as having two spaced ears located on the periphery of the head and pierced to receive a connector.

Fig. 6 shows a dress set of pins in which my improved pin stems are mounted, the different pins of the set being connected thru a chain, the top and bottom pins being provided with a single connector eye and the middle pin being provided with two connector eyes.

Figs. 7 and 8 are perspective views of modified eye formations on the pin stems.

It is found in the practical use of pin stems for use on beauty pins, brooches, particularly fraternity pins, and the like, often desirable to attach a connecting chain or cord

to the pin stems thereof so that different insignia and emblems may be attached to the pins, and so that the same may be fastened to the clothing of the wearer to prevent its becoming lost, and in some cases where a set of these pins is employed as in a dress set or the like, it is desirable that one or more of the pins of this set be provided with a plurality of connector eyes, whereby the different pins of the set may be attached together similarly to the manner disclosed in the drawing.

The piercing of an ear on the pin stem is found to be more practical and less expensive than providing such a device on the joint member or the catch member of a beauty pin or brooch; and the following is a detailed description of the present embodiment of my invention and showing the preferred construction of pin stems by which these advantageous results may be accomplished.

With reference to the drawings, 10 designates the base plate of a beauty pin or brooch on one end of which is mounted a joint member 11 and on the opposite end a catch member 12.

My improved pin stem 13 is preferably blanked from sheet stock into the form illustrated in Fig. 2, and the pierced shank portion 14 of which is then rounded, as illustrated in Fig. 3, and pointed as at 15, at one end; and the head portion 16 is left flat. This head portion is pierced as at 17, to receive the pivot pin 18 in the joint member 11 and this head end is also provided with an ear member or enlargement 19 which is also pierced as at 20, for the reception of a chain, cord, or other connector element 28, by which the beauty pin or brooch may be attached to the clothing of the wearer to prevent loss of the same. In some instances, a plurality of these pins or brooches may be connected together as in a dress set, as best illustrated in Fig. 6. In the construction of this device the ear may be positioned above the axis of the pin stem, as illustrated in Figs. 1 and 2, and in other instances it may be positioned to the rear of a vertical axis thru the pivot pin, as illustrated at 21, in Fig. 3, in which position this ear may serve as a back stop for 100

the pin stem to limit its backward swing. In still other instances, the ear may be positioned below the axis of the shank of the pin stem as at 22, in Fig. 4, while in still other instances the head of the pin stem may be provided with a plurality of pierced connector ears such as 23 and 24, as shown in Fig. 5. The ears, if pierced, may be bent at right angles to the pin head.

10 Where the beauty pins are used as a dress set connected together and there are but two in the set, but a single connector pierced ear need be employed, but where more than two are employed in intermediate pins, as illustrated at 25, in Fig. 6, are preferably provided with two connector eyes 23 and 24 so that the chain ends 26 and 27 may be readily attached thereto.

20 It is found in practice to be very simple and inexpensive to form these connector ears on the head of a pin stem at the time the whole is blanked and to pierce the same simultaneously with the piercing of the pivot eye in the head. In certain instances, it may be desirable to form the connector ears separately, and to fasten or otherwise secure the ears to the pin head. Such construction is particularly advantageous when the connector ear is turned at right angles to the pin head to lower the height of the beauty pins.

30 In Fig. 7 the eye 29 is rolled at right angles to the sheet stock, while in Fig. 8 the shank is formed from wire and the eye 30 rolled adjacent the pivotal mounting.

35 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A pin stem having a shank portion and a head portion, said head portion having pivot means and connector means additional thereto.

2. A pin stem having a point at one end and a pivot-receiving hole and a connector-receiving hole therethru, said pivot-receiving hole being located between the connector-receiving hole and said point.

3. A pin stem having a pivot-receiving hole and a connector-receiving hole therethru adjacent the pivot hole.

4. A pin stem having a rounded shank portion pointed at one end, a flat head portion at its opposite end having a pivot piercing and also a connector piercing therethru.

5. A pin stem having a rounded shank portion pointed at one end, and a flat head portion at its opposite end, said head being pierced to receive a pivot pin and having an enlargement pierced to receive a connector.

6. A pin stem having a rounded shank portion pointed at one end, a flat head portion

at its opposite end, said head being pierced to receive a pivot pin and having an ear extending from the periphery of said head pierced to receive a connector.

7. A pin stem having a shank portion and a head portion, said head having a pierced opening to receive a pivot and having a rearwardly-extending peripheral ear positioned to serve as a back stop and to receive a connector.

8. A pin stem having a shank portion and a head portion, said head having a pivot-receiving opening and a plurality of connector receiving openings therethru.

9. In testimony whereof I affix my signature.

ROGERS T. STAFFORD.
